6 Claims. (Cl. 53—180)

This invention relates to the machine subject of United States of America Patent No. 3,154,901. The present invention has been devised to modify such machine by:

- (i) Adapting the machine to operate vertically
- (ii) Incorporating means for making tubes of elastomeric material and progressively filling the same with fluid
- (iii) Dividing the tubes transversely by fusing means into conjoined compartments and, in one embodiment of the invention, severing the tubes along the fused seams into vendable containers
- (iv) In another embodiment adapting the machine incorporating (i), (ii) and (iii) to make, fill and sever two or more tubes simultaneously, and where the tubes are formed from strip material which is pre-printed with data relating to the contents of each container, to incorporate means to synchronise the components (ii) and (iii) with respect to the position of the printing on each container
- (v) In another embodiment incorporating in the tube at the position of each container to be formed means to take a sealing cap whereby the container can be used for partial, i.e., periodic, discharge of fluid and sealed after each discharge.

Broadly the invention provides a machine for making a tube from plastic strip by folding the strip and fusing the folded parts together, then charging the tube with fluid and transversely dividing and fusing the filled part of the tube into vendable containers of uniform length; said machine comprising a frame on which is mounted in descending order from the top, units A, B, C and D wherein unit A is a tube forming unit, unit B and unit D are tube pulling units and unit C is a tube transverse dividing and fusing unit; unit A comprises a hollow mandrel, tube forming means including a strip edge overlapping device and a tube fusing unit, and a fluid supply pipe passing through said mandrel; unit B comprises tube gripping jaws constructed to displace fluid in the tube upwardly, actuating means therefor and means to reciprocate unit B on said frame; unit C comprises transverse tube fusing bars and actuating means therefor; unit D comprises tube gripping jaws and actuating means therefor, unit D being connected to unit B for reciprocation therewith; means to synchronise the reciprocating movement of units B and D with the operation of units A and C.

A preferred form of the invention is illustrated in the accompanying drawings in which:

FIG. 1A is a perspective view of the upper section of the machine wherein strips of material are formed into tubes.

FIG. 1B is a similar view of the lower section of the machine wherein the tubes are formed into a series of containers.

FIG. 2 is a perspective view of one form of upper gripper mechanism, incorporating means for maintaining the tubes in running register and to prevent an excess pressure of fluid in the formed containers.

FIG. 3 is a section of plane 3—3 of FIG. 2.

2

FIG. 4 is a plan view of the components shown in FIGS. 2 and 3.

FIG. 5 is an enlarged perspective view of one of the tube forming and seaming units.

FIG. 6 is a plan view on the plane 7—7 in FIG. 1B showing the container forming mechanism.

FIG. 7 is a plan view on the plane 7—7 in FIG. 1B showing lower gripper mechanism.

FIG. 8 is a side elevation on the plane 8—8 in FIG. 1B.

FIG. 9 is a perspective view of mechanism to fix sealing caps on the formed tubes, when such are required for the containers to be formed.

The machine comprises a horizontal base 10 of four members, and two pairs of vertical posts namely a front pair 11 and a back pair 12 joined together by stays 13. The front posts 11 are of square cross section and the rear posts are of channel section. One of the rear posts 12 is extended as at 14 above the other posts, and carries spindles 15 upon which two rolls 16 of plastic strip 17 are mounted. The strips 17 are led over guide rollers 18, under stress relieving rollers to be described, and then pass downwardly into the components of units A which are identical and are now designated as units 19—20 and comprise the tube forming and filling means.

Unit 20 (see FIG. 5) consists of two spaced parallel horizontal top and bottom plates 21 of dielectric material, mounted on a metal frame work 22 fixed to the top of one of the posts 11. Axially aligned holes in the plates 21 have top and bottom tube forming and guide bushes 23a and 23 respectively therein and a mandrel tube 24 is concentrically positioned within and projects through each bush 23a—23. The mandrel 24 is supported by bracket 25 fixed to a supporting frame.

The guide rollers 18 orient each strip 17 so that as each strip is formed into a tube in the top bush 23a the edges of the strip travel through a strip edge overlapping device 26 and are overlapped thereby. In the device 26 one marginal edge 27 of the strip 17 enters an arcuate slot 28 and the other marginal edge 29 is positioned by a tongue 30 at the entrance to the slot 28. The device 26 ensures that the strip enters the bush 23a with one marginal edge 27 overlapping the other marginal edge 29. The strip 17 in this form passes through the top plate 21.

Opposed traverse slots 31 are formed in the plates 21 in diametric alignment with the bushes 23 and 23a. An electric seam fusing head 32 is slidably mounted in the traverse slots 31. The fusing head 32 is reciprocated into and out of fusing engagement with the overlapped edges of the strip between the bushes 23 and 23a by crank arms 33 on a shaft 34 mounted in bearings in the plates 21. The crank arms slidably engage in slots 36 in the fusing head 32.

A bell crank lever 37 is fixed to the top of the shaft 34 and one arm 38 is operatively connected to the piston rod 39 of a pneumatic cylinder 40 mounted on the upper plate 21. The other arm 41 of the crank 37 is provided with a threaded stop pin 42 which engages with a bracket 43 on the plate 21 when the piston rod 39 moves the fusing head 32 into fusing position.

The fusing head 32 is connected to a high frequency source of electric current which is generated in a cabinet 44 located alongside the machine and fragmentally shown in FIG. 1B. The strip 17 is intermittently drawn through the bushes 23a and 23, by mechanism yet to be described, for a distance slightly less than the distance between said bushes. When the strip 17 is stationary, the fusing head 32 is advanced by means of the piston rod 39 and the current is turned on with the fusing unit 32 in contact with the overlapped edges of the strip 17 to form a longitudinal fused seam 45. The seam 45 can be cooled by an air jet from the tube 46 secured to the lower plate 21, as the tube passes through the bush 23.

The formed tubes 35 emerge from the units 19 and 20 and are led down between the machine front posts 11 to a second high frequency fusing unit 47 mounted on the posts 11 by bolts 48 (see FIGS. 1B and 6).

Referring to FIG. 6, the fusing unit 47 comprises fuse bars 49 and 50 which flatten the tubes 35 and when high frequency current is passed through the bars 49 and 50 the tube walls are fused together transversely by a seam across the flattened parts. Feed tubes 51 extend into the bores of the hollow mandrels 24 in the seaming units 19 and 20 and down through the formed tubes to a position below the unit A.

A pump (not shown) is operated intermittently to pump fluid into the tubes 51. The discharge at each pump operation is metered to deliver a quantity of fluid less than the capacity of two of the ultimate containers 52. This minimises the likelihood of creating an excess pressure in the completed container 52. For some fluids gravity may be relied on in place of pumping means.

In the fusing unit 47 (see FIG. 6) there is a front plate 53 incorporating a saddle on which are mounted fusing bars 49. The front plate 53 is mounted on rods 54 which are horizontally slidable in gear boxes 55. The rear ends of the rods 54 have a yoke 56 thereon. A pair of guide rods 57 extend between the plate 53 and yoke 56 clear of the gear boxes 55, and a crosshead 58 is slidably supported on the rods 57. The fusing bars 50 are mounted on the front face of the crosshead 58.

Flanged wings 59 extend from the sides of the crosshead 58 and carry rods 60 which enter the gear boxes 55, spaced from and parallel to the rods 54. Gear tooth racks 61 are cut in the rods 54 and 60 within each gear box 55 and a pinion 62 in each gear box, meshes with the racks 61. The front plate 53 and crosshead 58 are thus interconnected so that movement of the crosshead, in one direction, will cause the plate 53 to move in the opposite direction. This movement is controlled by tandem pneumatic cylinders 63 which are secured to the yoke 56, and have their piston rods 64 connected to the crosshead 58. Stop pins 65 adjustably limit the movement in each direction. The manner of operation of the pneumatic cylinders will be described later.

As the strips are formed into the tubes 35 they are drawn downwardly by two gripper units 66 and 67 which are located respectively above and below the fusing unit 47, and are as shown in FIGS. 1B, 2, 3 and 7.

The lower gripper unit 67 is of similar construction to the fusing unit 47 except that the fusing bars 49 and 50 are replaced by gripper bars 68 and the same reference numerals plus the letter *a*, are used to refer to them. The gripper bars 68 are mounted on front plate 53a and crosshead 58a. The gripper bars 68 are moved by cylinders 63a as before but in this case the gear boxes 55a are vertically slidably mounted on the posts 11 through guides 69.

The lower ends of connecting bars 70 are bolted to the guides 69. The bars 70 extend upwardly, through apertures 71 in the gear boxes 55 (see FIG. 6), to the upper gripper unit 66 where they are bolted as at 72 to gear boxes 73 forming the sides of the upper gripper unit 66. The gripper unit 66 is slidably mounted on two vertical bars 74 secured to the posts 11. The gripper units 66 and 67 are thus joined by the bars 70 so that they are vertically movable in unison. This vertical movement is controlled by an upper and lower pneumatic cylinder 75 and 76 (see FIGS. 1A and 1B). The upper cylinder 75 is anchored to a cross member 77 fixed to the tops of the posts 11, and the lower end of its piston rod 78 is secured to a cross bar 79 fixed to the gear boxes 73 of the upper gripper unit 66 (see FIG. 8). The lower cylinder 76 is mounted in a cross member 80 fixed to the posts 11 below the gripper unit 67 and its piston rod 81 is connected to a second cross member 82 fixed to the guides 69 of the lower gripper unit 67.

Cables 83 are anchored to the cross member 82; they pass around pulleys 84 on shafts mounted between the

posts 11 and posts 12; the cables pass upwardly between the posts 12 and are anchored to the upper ends of the bars 70 which extend above the upper gripper unit 66. A counterweight 85 is fixed on each cable 83 so that the weight of the gripper units 66 and 67 is counter balanced. The cylinders 75 and 76 have therefore only to overcome the inertia of the gripper units 66 and 67 to effect vertical movement thereof.

The limits of the movement of the gripper units 66 and 67 is adjusted by nuts 87 and 88 screwed on the piston rod 78 on opposite sides of beam 86 through which the piston rod 78 freely passes (see FIG. 1A). The upper nut 87 is arranged to contact the upper face of the beam 86 and the lower nut 88 is located below and arranged to contact a horizontal stop bar 89 pantographically secured below the beam 86, by links 90. The position of the stop bar 89 is adjusted by a threaded rod 91 and a link system 92 which provides an accurate vernier adjustment for the upward movement of the piston rod 78. A sprocket 93 is secured to the rod 91 and carries an endless chain 94 so that the adjustment can be carried out by an operator near the base 10 of the machine.

In the form of the invention illustrated, the upper gripper unit 66 consists of two pairs of jaw units 95 and 96 (see FIGS. 2, 3 and 4). The unit 95 consists of two pairs of swing arms 97, each pair having fixed between them a jaw bar 98. The pairs of arms 97 are rotatably mounted on aligned shafts 99 fixed to the gear boxes 73 and they are geared together at the mounting position by gears 100. The jaw bars 98 are moved to open and closed position to grip and release a tube, by a pneumatic unit 101 connected to the swing arms 97 of one of the jaw bar units and anchored to the gear boxes 73.

Two pairs of shorter swing arms 102 are fixed on the shafts 99 and are geared together and rotatable in the gear housing 73 by the gears 122. The pairs of arms 102 each have tube gripping rollers 104 and 104a respectively part rotatably mounted thereon. Each roller 104-104a has an interengaging lug 105 and 105a and a spring carrier arm 106. The spring carrier arms 106 are held against stops 107 on the arms 102, by springs 108 at the position where the lugs 105-105a inter-engage. The roller 104a of each pair has an actuating arm 109 thereon, adapted to abut a regulator stop 110 which can be moved into a determined abutting position by an adjusting screw 111 raising or lowering an arm 112 on which a bar 113 is rotatably mounted as at 114. This bar 113 carries the regulator stop 110. Contact is made between the arm 109 and the stop 110 when the gripper unit 66 is lowered. The rollers 104 are moved to open and closed positions to grip or release a tube, by a pneumatic unit 115 (one of each pair) connected to one of the short arms 102 and also to the gear boxes 73.

In gripping position if the arm 109 of either one of the rollers 104a contacts its regulator stop 110 such roller 55 through its lug 105a will rotate its mating roller 104 and such pair of rollers will draw the tube gripped thereby downwardly a distance as predetermined by the adjusting screw 111. The respective regulator stops 110 are moved in and out of engaging positions by linkages indicated at 60 16 actuated by solenoids 117. The linkage-solenoid assemblies are mounted on the arms 112.

In operation when the jaw bars 98 are moved to closed position they displace upwardly a quantity of fluid in the tubes 35 slightly in excess of the area of the tube to be closed by the fusing means. Then the rollers 104-104a, which are preferably made or faced with an elastomeric material, are closed on the tube and seal off fluid above them. While the rollers 104-104a remain closed the jaw bars 98 are opened and the jaw unit carrier moves downwardly a distance predetermined by adjustable stop screws 118 in brackets 119 fixed to the unit 66 (see FIG. 2). The stop screws 118 are in register with a cross bar 120 fixed to the posts 11. The roller assembly carries with it tubes 70 35 with the filled but unloaded part to fusing position.

If in the case of tubes formed of pre-printed strip material, the printing on the tubes or one of them is not in register with markings on the machine—an out of register position would normally be above the rollers 104-104a—the machine operator adjusts the regulator stop 110 of the out of register tube and moves it into contact position (see FIG. 3). The rollers holding the out of register tube by abutting the stop are thus given a part rotary movement and the tube gripped thereby is drawn downwardly the additional distance as set by the adjusting means.

Adjustment of the vertical distance between the upper and lower gripper jaw units 66 and 67 and consequently the length of a container is effected by a toothed rack 121 (see FIGS. 2 and 8), on one edge of the bars 70 which meshes with gears (not shown) in the gear boxes 73. The bolts 72 must be removed to effect this adjustment; a series of holes 124 are formed in the bars 70 to allow for the adjustment.

In order to time the actuation of the various pneumatic cylinders controlling the functions of the machine a master air flow control valve 125 (FIG. 1B) is provided. This valve is mounted on a platform 126 fixed to the side of the machine. The valve 125 is controlled by a series of motor driven cams 127.

In operation, the gripper jaw units 66 and 67, with their jaws 98 and 68 in the open position, are raised from the dotted positions shown in FIG. 8, whilst the bars 49 and 50 of the fusing units 47 are gripping and fusing the tubes 35. The gripper units 66 and 67 then close about the tubes 35 and then the fusing unit 47 opens to release the tubes. The gripper units 66 and 67 are then drawn downwardly pulling the tubes 35 with them. The fusing bars 49 and 50 are then advanced to contact the tubes and fuse them so that containers 52 are formed therein. Whilst this is occurring the gripper units 66 and 67 have been opened and raised to the upper position to commence another cycle.

As described, two continuous chains of containers 52 are formed. If desired, the gripper bars 68 of the lower gripper unit 67 can be supplemented by cropping dies shown in dotted lines in FIG. 8 and indicated at 68a, mounted on the plate 53a and crosshead 58a. These cropping dies will cut through the tubes at the fused sections.

Where cropping dies are used, a timed movement conveyor is provided to pick up the containers as they are severed. Such a conveyor is shown in dotted lines in FIG. 9 and indicated by the reference 128.

To reduce stress in the strip 17 and in the length of tube between the seaming and forming units 19 and 20 and the gripping units 66 and 67, a further pneumatic cylinder 129 (FIG. 1A) is mounted on the extension 14 of the post 12. Rollers 130 are carried by the piston rod 131 of this cylinder 129, and the rollers are moved downwardly against the strips 17 between the guide rollers 18. This occurs when the strips 17 are stationary within the seaming units 19 and 20 and fusing units 47, so that a length of each strip 17 is unrolled from the rolls 16. The rollers 130 are then returned to their original upper position so that slack is left in the strips 17 which will be taken up on the next downward movement of the strips 17 through the seaming units 19-20.

The nature of the material from which the containers are made is such that stretching can occur immediately after the fusing unit 47 has operated, if the full weight of the filled container has to be taken by the heat softened transversely seamed portion of the tube. To counteract this the gripping bars and/or the fusing bars and/or the cropping dies can be cooled as indicated by the air tube 46.

In the case of a single tube forming and filling unit, the tube running register mechanism of FIGS. 2, 3 and 4 is not required, but in single tube forming, filling and sealing it is necessary to provide a cavity in the upper gripper jaws 98 to constitute a bleed for fluid displaced by these gripper jaws. However, the apparatus of FIGS. 2, 3 and 4

can be adapted to serve the same function in a single tube machine.

The mechanism of FIGS. 2, 3 and 4 is essential to machines forming, filling and sealing two or more tubes, where such tubes are formed from strip material which is pre-printed with data relating to the contents of each container.

Referring to FIG. 9, a conveyor 132 is arranged to feed sealing caps 133 from a source of supply and from an unscrambling mechanism (not shown), to a loading position where, in the embodiment illustrated, four tubular arms 134 located in a common vertical plane on a crosshead 135 on a lever 136 fulcrumed on an arm 137 fixed to the machine. The lever 136 is adapted to be swung in a horizontal plane to move the arms 134 into and out of register with a tube 35 by a pneumatic unit 138 mounted on a bracket 139. The crosshead 135 is rotated to bring the arms 134 into successive register with a cap pick-up position indicated at 139, and with a tube 35 immediately below the tube forming unit, by pneumatic unit 140 and linkage 141. The linkage 141 rotates the crosshead 135 by a ratchet wheel and pawl located as indicated at 142. At the cap pick-up position, a solenoid actuated plunger 143 pushes a cap 133 into the arm 134 in register therewith, the cap 133 being held projecting from arm 134 by its flange 144.

When the cap 133 is brought into register with tube 35, it is fused thereon. The arms 134 and the mandrel 24 constitute the fusing electrodes.

A punch (not shown) may be incorporated to punch holes in the strip 17 before it is formed into a tube, the holes being formed to register with the arm 134 located at the cap fusing position.

Adjusting means are provided to maintain the caps in registering position with the holes punched in the strip. To effect this the arm 137 and bracket 139 are vertically slidably mounted on the frame 22 by vertical slide ways 145 (FIG. 1A) and are connected to levers 146 which are pivotally secured to the frame 22 and 147. The levers 146 are adapted to be moved by threaded rods 148 which are rotatably secured to a control position (not shown) near the base of the machine. By rotating the rods 148, the operator can raise or lower the capping unit to effect the required register adjustment.

I claim:

1. A machine for making a tube from plastic strip by folding the strip and fusing the folded parts together, then charging the tube with fluid and transversely dividing and fusing the filled part of the tube into vendable containers of uniform length; said machine comprising a frame on which is mounted in descending order from the top, units A, B, C and D wherein unit A is a tube forming unit, unit B and unit D are tube pulling units and unit C is a tube transverse dividing and fusing unit; unit A comprises a hollow mandrel, tube forming means including a strip edge overlapping device and a tube fusing unit, and a fluid supply pipe passing through the said mandrel; unit B comprises tube gripping jaws constructed to displace fluid in the tube upwardly, actuating means therefor and means to reciprocate unit B on said frame; unit C comprises transverse tube fusing bars and actuating means therefor; unit D comprises tube gripping jaws and actuating means therefor, unit D being connected to unit B for reciprocation therewith; means to synchronise the reciprocating movement of units B and D with the operation of units A and C.

2. A machine according to claim 1 including means to fix sealing caps on the tube at the position of each container to be formed.

3. A machine according to claim 1 including a base, a pair of front posts and a pair of rear posts upstanding from the base, an upwardly disposed extension on one of the rear posts, a roll of tube forming strip material mounted on a spindle fixed on the extension, guide rollers mounted on the extension for guiding the strip material

passing thereover to the tube forming unit, and a stress relieving roller mounted for reciprocation on an arm on the extension, said stress relieving roller being located above the strip between the guide rollers and being moved downwardly to engage the strip to relieve tension on the strip prior to feeding the strip to the fusing unit.

4. A machine according to claim 1, wherein the tube forming unit comprises spaced, parallel, horizontal top and bottom plates of dielectric material mounted on a framework fixed to the top front of the machine frame, axially aligned holes in the plates, top and bottom bushes fixed in the holes, said top bush being a tube forming bush including the strip edge overlapping device, said strip edge overlapping device comprising an arcuate slot formed through the top plate and communicating at one of its ends with the tube forming bush, and a tongue in the tube forming bush at the entrance from said tube forming bush into the arcuate slot, said slot extending past the tongue, said bottom bush being a guide bush, the mandrel projecting concentrically through the bushes, an electric seam fusing head slidably mounted in and between the plates, and means to reciprocate the seam fusing head into and out of engagement with the overlapped edges of the strip.

5. A machine according to claim 1 adapted to make and fill at least two plastic tubes simultaneously and to fill and divide them into vendable containers wherein the tube gripping jaws of unit B consists of two pairs of long swing arms rotatably mounted on aligned shafts and geared together in pairs at the mounting positions, each pair of long arms having a pair of jaw bars fixed between them, one arm of each of the pairs of long arms having an actuating pneumatic unit connected thereto and anchored

to supporting means; two pairs of shorter swing arms rotatably mounted with said shafts and geared together in pairs through said shafts, each pair of shorter arms having tube gripping rollers part rotatably mounted thereon, each roller having an interengaging lug and a spring carrier arm thereon, said spring carrier arms being held against stops at the position where the lugs inter-engage one above the other, the roller of each pair with the upper engaging lug having an actuating arm located to abut a regulator stop whereby the rollers can be rotated by the lugs, one arm of each pair of shorter arms having an actuating pneumatic unit connected thereto and anchored to supporting means.

6. A machine having tube gripping jaws according to claim 5, including means to open and close the jaws, firstly the jaw bars on the long arms to displace upwardly a quantity of fluid in the tubes gripped thereby and secondly the rollers on the shorter arms to hold the displaced fluid above the long arm jaws while the long arm jaws are retracted, the tubes moved to fusing position and the transverse fusing operation completed.
